UNITED STATES PATENT OFFICE.

JENS JACOB LASSEN AND VILHELM FREDERIK HJORT, OF LONDON, ENGLAND.

APPARATUS FOR DELIVERING MEASURED QUANTITIES OF LIQUID.

1,069,017.

Specification of Letters Patent.

Patented July 29, 1913.

Application filed April 14, 1910. Serial No. 555,349.

To all whom it may concern:

Be it known that we, JENS JACOB LASSEN and VILHELM FREDERIK HJORT, subjects of the King of Denmark, both residing at 5 London, in England, have invented certain new and useful Improvements in Apparatus for Delivering Measured Quantities of Liquid, of which the following is a specification:

10 This invention relates to apparatus for delivering liquids of the type wherein two pistons relatively adjustable on a spindle are periodically moved within a casing to discharge a measured quantity of liquid.

15 The invention is particularly applicable to water softening or purifying plants where measured quantities of liquid such as milk of lime containing solid particles in suspension have to be periodically delivered 20 from a tank.

According to this invention the casing within which the valves are moved is capable of adjustment so that when the space between the two valves is varied the distance between the admission and discharge 25 ports in the casing can be similarly adjusted, thus permitting variation between wide limits without the movement of the valves and the size of the admission and 30 discharge ports being altered. The axial opening or the one at the upper end of the casing constituting the admission port is closed by a lift valve, positively connected to a piston valve controlling the discharge 35 ports near the lower end of the casing.

One construction of valve in accordance with this invention is illustrated by way of example in the accompanying drawing in central vertical section.

40 In the construction illustrated the valve is shown as applied to the base of a tank A from which measured quantities of liquid are to be delivered whenever the valve is actuated. Screwed into the base of the 45 tank A is a bushing B the upper end of which forms a guide for a lift valve C carried by a rod D adapted to be reciprocated in some known manner. The parts are, as usual, so constructed and arranged that the

50 valve C is normally maintained in its closed position being lifted by actuation of the rod D. The bushing B is internally screw threaded throughout the greater portion of its length and has screwed into it 55 a liner E having openings E' formed near its lower end. The liner E together with

the bushing B constitutes the casing of a cylindrical chamber for the flange C' of the valve C; this valve controlling the upper open end of the cylinder through which admission takes place. Extensions C² are formed on the under surface of the valve C which bear against the walls of said chamber and act as guides for the valve in its raised position. Mounted on the 60 valve C is a rod or spindle F carrying a piston G also working within the liner E and adapted to control the openings E' through which discharge takes place. The position of the piston G relatively to the 65 discharge ports E' is such that when the upper valve C is in its raised position the piston G prevents the escape of liquid through the discharge ports, the length of the flange C' being equal to the maximum effective length of opening of the discharge ports. 70

The operation of the valve is as follows: When the valve rod D is operated the valve C is raised and places the open end of the 80 cylinder in communication with the tank A; as soon however as the admission port is thus uncovered the piston G has moved upward with the valve C and is in operating position to prevent escape of liquid through 85 the discharge ports E'. A quantity of liquid is therefore admitted into the cylinder determined by the dimensions of the cylinder and the relative positions of the two valves. When the lift valve falls back 90 on to its seat (as shown in the drawing), the piston G uncovers the discharge ports E' but not before the flange C' has closed the admission ports. The liquid contained between the two valves is therefore delivered 95 through the openings E', the inclined inner surface of the piston G insuring that complete discharge takes place.

When it is desired to vary the amount of liquid discharged at each operation of the 100 valves, the relative positions of the two valves are adjusted. To this end the spindle F is conveniently screw-threaded so that the piston G can be adjusted to the required position thereon.

105 Since the amount of liquid delivered from any particular sized cylinder is determined solely by the distance between the two valves, the relative positions of the discharge ports and lower piston must remain constant. To 110 that end the liner E is screwed in or out of the bushing B so that the ports E' are fully

open when the upper piston is in the closed position shown. In the example illustrated if the distance between the pistons be increased to the maximum amount and the liner E screwed out to a corresponding extent, the extensions C² of the valve C would be deprived of a proper guiding surface and the capacity of the cylindrical space between the two valves would unintentionally be increased. If desired however when the position of the piston G is altered a new liner E of the required length may be inserted. The liner E preferably has a squared portion E² on its lower end whereby it may be rotated within the bushing and a locking ring H is conveniently provided to maintain the liner in its adjusted position.

The mechanism employed to actuate the valve rod D may be of any suitable known type.

What we claim as our invention and desire to secure by Letters Patent is:—

1. In an apparatus for delivering measured quantities of liquid, the combination of a chamber of variable capacity adapted to contain the amount of liquid to be delivered at each operation of the apparatus, and provided with inlet and discharge ports, valves controlling said ports, connections between the valves permitting relative adjustment thereof to correspond with variations in the capacity of the chamber and insuring that the inlet to the chamber shall be closed before the outlet therefrom is opened, and means for simultaneously moving the valves.

2. In apparatus for delivering measured quantities of liquid, the combination of a tank having an aperture, an open ended bushing screwed into said aperture, a liner having outlet ports and adjustable relatively to the bushing, the bushing and liner forming a vertical cylinder having an open upper end and discharge ports in its lower end, a valve adapted to keep said open end normally closed, a valve adapted to close the discharge ports and having an inclined face,

a rod connecting the two valves, and permitting adjustment of the outlet valve on the rod relative to the inlet valve, guides on the inlet valve extending into the chamber and coöperating with a side wall thereof, and means for reciprocating the valves.

3. In an apparatus for delivering measured quantities of liquid, the combination of a casing adapted to contain the entire quantity of liquid to be discharged at a single operation of the apparatus and comprising two members telescopically connected and provided respectively with inlet and outlet ports, valves controlling the ports, connections between the valves permitting adjustment thereof to correspond with variations in the capacity of the measuring chamber and normally maintain the inlet to the chamber closed, and means for moving the valves.

4. In an apparatus for delivering measured quantities of liquid, the combination of a casing of variable capacity having an inlet opening in one end and a discharge opening in its side adjacent the other end, said casing being adapted to contain the entire quantity of liquid to be discharged at a single operation of the apparatus, a valve movable to and from a position to close the inlet opening, a second valve adapted to control the outlet opening and so connected with the inlet valve that said openings can not be simultaneously operative, the connections between the valves permitting relative adjustment thereof to correspond with variations in the capacity of the measuring chamber, and means for actuating the valves.

In testimony whereof we have signed our names to this specification in the presence of two subscribing witnesses.

JENS JACOB LASSEN.
VILHELM FREDERIK HJORT.
